UNITED STATES PATENT OFFICE.

ADAM L. LITZNER, OF ALLENVILLE, MICHIGAN.

WELL-DRILLING MACHINE.

Application filed October 1, 1926. Serial No. 138,916.

This invention relates to well drilling apparatus, and comprehends a structure mounted on the chassis of a motor operated vehicle, and designed to be quickly and conveniently arranged in position for use, and operated from the traction wheels after the latter have been jacked or spaced from the ground.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

- 20 Figure 1 is a side elevation.
- Figure 2 is a rear end elevation.
- Figure 3 is a sectional view on line 3—3 of Figure 2.
- Figure 4 is a detail view of one of the traction wheels showing the inactive position of the operating means for the walking beam.
- Figure 5 is a similar view showing said operating means operatively associated with said wheel.

Figure 6 is a fragmentary plan view of the walking beam.

Figure 7 is a fragmentary view showing the working end of the walking beam and the connection between the latter and the reciprocating beam.

Figure 8 is a view taken at a right angle to Figure 7 of the cushioning means for the walking beam.

Figure 9 is a fragmentary view of the upper end of the reciprocating beam.

Figure 10 is a fragmentary view showing the manner of folding the jack beneath the frame of the machine.

Figure 11 is a view of a modified construction showing the neutral position of the crank arm.

Figure 12 is a similar view showing the crank arm in a position for use.

Figure 13 is a view showing the means for holding the crank arm in any given position.

Figure 14 is a top plan view of Figure 18.

Figure 15 is a view of another modified construction showing the crank arm operatively associated with the clutch.

Figure 16 is a similar view showing the inactive position of the clutch.

Figure 17 is a view taken at a right angle to Figure 15 and partly in section.

Referring to the drawing in detail A indicates generally the running gear of a motor operated vehicle, wherein 10 represents the traction wheels.

Rising from the frame of the running gear are spaced parallel standards 11 and 12, which are connected by the spaced parallel members 13, defining an auxiliary frame upon which the boom 14 is pivotally supported, this boom having associated therewith the reciprocating beam 15 which slides through a suitable bearing in the upper end of the boom. This boom normally lies in a horizontal position as shown in Figure 1, and is adapted to be swung to a vertical position at one end of the machine when its use is desired. The boom may be elevated and lowered in any suitable manner. Journalized between the standards 11 is a drum 16 about which the cable 17 is adapted to be wound and unwound therefrom as the occasion may require. Also pivoted between the standards 11 is a walking beam 18 including the shaft 19 upon which is mounted a guide pulley 20, over which the cable 17 is trained as shown in Figure 1. An additional guide pulley 21 is supported adjacent the apex of the walking beam as shown in Figure 6, the cable 17 being trained under the pulley 21, and then extended and trained over the pulley 22 carried by the upper end of the reciprocating beam 15. The well drilling tool (not shown) is of course suspended from the free end of the cable 17, and incident to the operation of the walking beam 18, the said tool is raised and lowered in the well as will be readily understood.

As shown in Figure 7 the reciprocating beam 15 is yieldably connected with the walking beam 18, to cushion the operation of the well drilling tool, and this connection includes a yoke 23 projecting from the lower end of the reciprocating beam 15 and provided with longitudinal slots 24. An eye bolt 25 slides through the closed end of the

yoke 23, the eye of said bolt being connected by a pin 26 with the adjacent extremities of links 27 depending from the adjacent end of the walking beam 18, the pin 26 sliding in the slots 24 above mentioned. Threaded on the eye bolt 25 are nuts 28, between which and the closed end of the yoke 23 is arranged a cushioning spring 29, which encircles the bolt 25 as illustrated.

10 The walking beam itself is also yieldably connected with the frame of the vehicle or machine to cushion the operation of said beam as clearly shown in Figure 8. For this purpose an inverted U-shaped bracket 30 is secured to the frame of the machine, while slidably through the closed end of said bracket is a rod 31, the latter depending from a shaft 32 carried by the walking beam 18. A cushioning spring or other yieldable element 33 encircles the rod 31 and is interposed between the closed end of the bracket 30 and nuts 34 carried by said rod.

While any suitable means may be employed for operating the walking beam 18, I preferably employ the mechanism clearly illustrated in Figures 1, 4, and 5 respectively, wherein it will be noted that the beam 18 is actuated from the rear wheels 10 of the machine. These wheels are of course operated by the motive power of the machine, and when employed to operate the beam 18, the machine is suitably jacked to space the wheels 10 from the ground. This mechanism includes a curved bar 35 which is pivoted as at 36 on the outside of the wheel, it of course being understood that both wheels are constructed and equipped in the same manner. Each bar 35 is provided with a plurality of spaced notches 37 adapted to singly receive the crank pin 38 projecting from a link 39 which is pivoted upon the wheel as at 40. Connecting the crank pin 38 with the adjacent end of the walking beam is a connecting rod 41, so that when the parts are operatively associated, the beam is actuated incident to the rotation of the wheels 10. The throw of the beam 18 is controlled by adjusting the crank pin 38 to arrange it in different notches 37, which can be conveniently accomplished, due to the fact that the bar 35 is pivoted and can be easily raised with relation to the pin 38, to allow the link 39 to be properly positioned with relation to the bar. After the pin 38 has been arranged in the desired notch 37, the bar is held against pivotal movement by a suitable cam lock 42 arranged upon the wheel. It will be noted upon inspection of Figure 1, that when the link 39 is arranged in a true vertical position, centrally of the bar 35, the wheels 10 may rotate without effecting the walking beam 18, thus allowing the machine to be moved from place to place when desired.

When it is necessary to lower the tool

within the well, or to remove it therefrom, the drum 16 is actuated to wind the cable 17 about the drum or unwind it therefrom as the occasion may require. For the purpose of operating this drum I employ grooved wheels 43, one for each of the traction wheels 10, and which wheels 43 are bolted or otherwise suitably secured to the brake drums for the wheels 10. Links 44 depend from the shaft 45 journaled in the uprights 11, and journaled between the lower ends of these links is a shaft 46 upon which is mounted wheels 47 of the configuration clearly shown in Figure 2 to fit within the grooves of the wheels 43, the wheels 47 being frictionally driven from the wheels 43 as will be readily understood. The wheels 47 of course rotate the shaft 46 which has mounted thereon a small toothed wheel 48 over which and a larger toothed wheel 49 carried by the shaft 45 of the drum, an endless chain 50 is trained, so that the drum is rotated from the shaft 46. The wheels 47 however are only moved into operative association with the wheels 43 when it is desired to wind the cable 17 about the drum 16 or unwind the cable therefrom, and consequently the wheels 47 are movable with the links 44 toward and away from the wheels 43. For this purpose the links are connected to a rod 51 which in turn are connected with the adjacent end of a lever 52 pivoted as at 53, the other end of said lever being connected to a rod 54 which extends to a hand operated lever 55, by means of which the movement of the wheels 47 toward and away from the friction wheels 43 can be conveniently controlled. A sand line reel 56 is also operated from the friction drive wheels 43, and can be adjusted toward and away from the latter in any suitable manner.

The jacks for raising the rear wheels from the ground are indicated generally at 57 and are pivoted between links 58 which in turn are pivoted on the side members of the frame of the vehicle. These links are provided with eyes 59 adapted to be engaged by hooks 60 to hold the links 58 folded against the sides of the frame as shown in Figure 10, during which time the jacks are also folded beneath the frame of the vehicle, and held in this position by a yoke 61. Manifestly by releasing the jacks from the yoke 61, and separating the links 58 from the hooks 60, the jack structure can be quickly and conveniently lowered into engagement with the ground and subsequently adjusted to elevate the wheels 10.

Manifestly I have devised a well drilling apparatus which can be conveniently moved from place to place by the motive power of the machine, and said motive power subsequently used to operate the well drilling apparatus. The mechanism for operating the

walking beam 18 can also be quickly adjusted to vary the throw of said beam, while the power and speed of the apparatus can also be easily regulated. The apparatus can be quickly set up for use, and the desired results accomplished with a minimum of time and effort.

In Figures 11 to 14 inclusive I have illustrated a modified construction of the means for operating the walking beam, and which means includes a crank arm 60 which has associated therewith a curved bar 61. In this form of the invention the curved bar is formed on the crank arm 60, the crank arm being connected with the walking beam in the same manner as in the preferred form of the invention, namely by a connecting rod 62. The curved bar is provided with spaced notches 63 along its outer edge and adapted to singly receive a locking pin 64 which is slideable through the wheel 65. This pin 64 is carried by a yieldably mounted disk 66 which normally holds the pin 64 out of the notches 63, and which disk is moved in the direction of the wheel to force the pin into engagement with a particular notch of said bar by the means clearly illustrated in Figures 13 and 14. This means includes a bell crank lever 67 operated from a remote point by a rod or cable 68, one branch of said lever having connected therewith a yoke 69 which has journaled therein a wheel 70. When the cable 68 is actuated, the lever 67 is moved upon its pivot throwing the wheel 70 into engagement with the disk 66, and thereby forcing the pin 64 outwardly into engagement with a particular notch on the bar 63. When the pin engages the innermost notch as shown in Figure 11 the crank is held in its neutral position; while Figure 12 illustrates how the crank can be shifted to different positions and held in said position by the pin 64.

In Figures 15 to 17 inclusive I have shown another form of the invention, wherein use is made of a straight crank arm 71 which is loosely mounted on the shaft 72, and provided with a plurality of openings 73, whereby the connecting rod 74 of the walking beam can be adjusted along the length of the crank arm to vary the throw of the beam as will be readily understood. In connection with the crank arm 71 I employ a substantially U-shaped clutch member 75 which is normally arranged between the crank arm 71 and the wheel 76, the clutch member being supported by fingers 77 to slide through the wheel 76. These fingers 77 are connected with a spring pressed disk 78 in the same manner as the pin 64 above mentioned, and which disk normally holds the U-shaped clutch member between the wheel and the crank arm 71 as shown by dotted lines in Figure 16. When it is de-

sired to use the crank arm for the purpose above mentioned, it is only necessary to pull upon the cable 79 which throws the disk 78 in the direction of the wheel 76, thereby moving the U-shaped clutch member outwardly to a position where it can straddle the adjacent end of the crank 71 as shown in Figure 15.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

1. In a well drilling machine, a motor operated wheeled frame, a boom pivotally mounted thereon and adapted to be elevated for use, a reciprocating beam associated with said boom, a pulley on said beam, a drum, a tool operating cable leading from the drum and trained over said pulley, means for operating said beam from the wheels of the frame, means for jacking said wheels above the ground, and means driven from said wheels for rotating said drum for the purpose specified.

2. In a well drilling machine, a motor operated wheeled frame, a boom pivotally mounted thereon and adapted to be elevated for use, a reciprocating beam associated with said boom, a pulley on said beam, a tool operating cable trained over said pulley, means for operating said beam from the wheels of the frame when the latter are spaced above the ground and a jack structure for raising said wheels and adapted to be folded beneath the frame of the machine when not in use.

3. In a well drilling machine, a motor operated wheeled frame, a boom pivotally mounted thereon and adapted to be elevated for use, a reciprocating beam associated with the boom, a pulley on said beam, a drum, a tool operating cable extending from said drum and trained over said pulley, means for operating said beam from the wheels of said frame, means including friction driven wheels operated from the wheels of the frame for rotating said drum, and a sand reel actuated from the wheels of said frame.

4. In a well drilling machine, a motor operated wheeled frame, a boom pivotally mounted thereon and adapted to be elevated for use, a reciprocating beam associated with said boom, a pulley mounted on said beam, a drum, a tool operating cable leading from the drum and trained over said pulley, means for operating said beam from the wheels of the frame, means for rotating said drum and including wheels frictionally driven from the

wheels of the frame, and means for moving said friction driven wheels toward and away from the wheels of the frame.

5. The combination with a wheeled frame having a walking beam mounted thereon, of means for operating the walking beam from the wheels of the frame, said means including a crank arm pivoted on said wheel, a

curved bar having a plurality of notches adapted to singly receive the crank of said arm, a cam for holding said bar associated with said arm, and a connecting rod connecting the arm with said walking beam.

In testimony whereof I affix my signature.

ADAM L. LITZNER.
